UNITED STATES PATENT OFFICE.

EDWARD HOFFMAN, OF LOGAN, UTAH.

MORTISE LOCK.

Application filed October 23, 1922. Serial No. 596,378.

To all whom it may concern:

Be it known that I, EDWARD HOFFMAN, a citizen of the United States, residing at Logan, in the county of Cache and State of Utah, have invented certain new and useful Improvements in Mortise Locks, of which the following is a specification.

The invention relates to mortise locks, and has as an object the provision of a latch and lock of this nature which may be inserted in an opening provided by a bit without the use of a chisel.

A further object of the invention is the provision of a device of this nature which has an exceedingly simple locking mechanism. A further object of the invention is the provision of such a device which shall be cheap to manufacture and simple to assemble and made of few parts.

An illustrative embodiment of the invention is shown in the accompanying drawings, in which—

Fig. 1 is an elevation of a portion of a door with the lock in place;

Fig. 2 is a central horizontal section showing the device in a locked position;

Fig. 3 is a central vertical section on line 3—3 of Fig. 2;

Fig. 4 is a detail section showing the bolt retracted;

Fig. 5 is a detail side elevation, partly in section, of the showing of Fig. 4, and

Fig. 6 is a perspective view of a key to operate the lock as shown.

The lock is shown as comprising a casing 10, which is tubular in form, and has a flange 11 for securing the device in place. A single bolt 12 is shown having the beveled surface 13 at its end for coaction with a keeper and as being tubular in form and open at its rear end. The bolt 12 is of such a size as to slide freely within the casing 10. To provide an abutment for the spring 14 which, acting in compression, projects the bolt 12, a plug 15 is provided which is rendered immovable with relation to the casing 10 by means of a screw 16 passing through a plane walled opening in the plug 15 and which takes into the screw threads in the walls of the casing 10 at 17 and 18.

To provide for movement of the bolt 12 in the casing 10 slots 19 are provided in the walls of the tubular bolt 12 which slots move past the screw 16 as the bolt 12 is retracted and projected in use.

To lock the bolt 12 against movement

when desired a screw 20 is provided which is threaded upon its periphery and takes into a threaded hole 21 in the plug 15. When it is desired to lock the bolt a key 22, the end 60 of which is shaped like a screw driver, and thereby is adapted to coact with the slot 23 in the end of the locking member 20, is inserted in the keyhole 24 and the screw is turned in either direction to a position such as shown in Fig. 2, when the wall of the tubular bolt 12 will be rendered immovable by projection of the screw bolt 20 at one side or the other of the plug 15. The shape of the keyhole 24 is such that the key 22 may 70 coact with the projection 25 thereof, and if left in the lock the bolt 20 will be rendered immovable by an unauthorized person from the other side of the door, and more over there being no opening entirely through the 75 door it will be impossible for such person to work the key out, as is possible with locks of usual form. To bring about a coaction between the key and the notch 25, the key is inserted into the slot in the screw 20 far 80 enough to secure an operative engagement. The screw is then turned until the key has traveled through the keyhole 24, as far as possible, without interference by the notch 25. Then with the key in the proper position of rotation it is shoved up into the slot in the screw and into the notch coincidentally, thereby locking the screw against rotation 85 from the opposite side of the door.

To retract the bolt 12 manually, when not locked, a squared shaft 26, provided with knobs 27 at its ends, according to the usual practice, is passed through openings 28 in the casing 10, slots 29 being provided in the walls of the bolt 12 to permit reciprocation of the bolt past the shaft, and a bolt operating member 30 is provided upon the shaft. To permit action of the member 30 slots 31 are provided in the wall of the casing 10 which slots 31 are in alignment 90 with the slots 19 in the bolt already described. With the lock in the position shown in Fig. 3 if the bottom of the shaft 26 be revolved to the left the member 30 will impinge upon the rear end of the lower slot 19, as at 32, thereby forcing the lock to the rear and into the position shown in Figs. 4 and 5. The revolution of the shaft in the opposite direction will cause the member 30 to coact with the rear end of the 100 upper slot 19 in reverse manner from that described; with retraction of the bolt 12.

When the knob is released the action of spring 14 will again project the bolt to its normal position.

A keeper 33 having a circular hole therein may be secured upon a door-jamb for coaction with the bolt 12. Minor changes may be made in the physical embodiment of the invention without departing from its spirit.

10 Having thus described my invention what I claim as new and desire to secure by Letters Patent is—

15 1. A mortise lock comprising, in combination, a tubular shell, a tubular bolt reciprocable therein, a plug immovably secured in said shell, a spring abutting against said plug and said bolt for projection of the bolt, and means for locking said bolt to said plug.

20 2. A mortise lock comprising, in combination, a tubular shell, a tubular bolt reciprocable therein, a plug immovably secured within said shell and placed within said tubular bolt, a spring abutting against said plug and said bolt, said bolt having slots for coaction with a cam, a knob shaft, a cam on said shaft for actuation of said bolt by coaction with said slots.

25 3. A mortise lock comprising, in combination, a tubular shell, a tubular bolt reciprocable in said shell, a plug within said bolt

immovably secured to said shell, locking means in said plug adapted to be projected therefrom to lock said bolt against movement.

35 4. A mortise lock comprising, in combination, a tubular shell, a tubular bolt reciprocable therein, a plug within said bolt immovably secured to said shell, a spring within said bolt abutting against said plug and an end of said bolt, a screw threaded opening in said bolt, a screw threaded locking plug coacting with said opening, said bolt having openings aligning with said screw threaded opening whereby revolution of said screw threaded plug will project the same into an opening in said bolt to lock the same.

40 5. A mortise lock comprising, in combination, a tubular shell, a tubular bolt reciprocable therein, a plug within said bolt immovably secured to said shell and having a screw threaded perforation, a screw threaded locking plug in said perforation, said bolt having openings in alignment with said screw threaded opening when the bolt is projected, a face plate having a keyhole therein in alignment with said openings, and means to prevent revolution of a key in said keyhole when said plug is in locking position.

45 55 60 EDWARD HOFFMAN.
